Inventor

John Scanlan

United States Patent Office.

JOHN SCANLAN, OF CHICAGO, ILLINOIS.

Letters Patent No. 70,028, dated October 22, 1867; antedated October 16, 1867.

IMPROVEMENT IN THE CONSTRUCTION OF ROOFING.

The Schedule referred to in these Letters Patent and making part of the same.

TO ALL WHOM IT MAY CONCERN:

Be it known that I, JOHN SCANLAN, of Chicago, in the county of Cook, and State of Illinois, have invented a new and useful Improvement in Felt-Roofing; and I do hereby declare and make known that the following is a full, clear, and exact description of the same, reference being had to the accompanying drawings, and the letters and figures marked thereon, which form part of this specification.

My invention consists in a novel arrangement of layers of felt, or its equivalent, with a layer of canvas or cloth, forming together an article of ready-made felt-roofing superior in point of strength and durability.

To enable those skilled in the art to understand how to make and use my invention, I will proceed to describe the same with particularity, making reference in so doing to the aforesaid drawings, in which—

Figure 1 represents my invention as applied in layers or strips upon a roof, and

Figure 2 is a transverse sectional view of one of the strips of roofing.

Similar letters of reference denote the same parts of my invention in the different figures.

A A represent the strips of the prepared roofing as arranged in consecutive layers, overlapping each other in the same manner that the courses of shingles overlap each other on a shingled roof. Each strip, A, of the roofing is made in the following manner: The lower stratum, marked a, consists of a layer of felt, of the required width and any desired length, saturated with coal tar, or its equivalent. The next layer, b, consists of canvas or cloth, which has been shrunk and saturated with coal tar, and is of the same width and length as the strip c, and is arranged upon it in the manner shown, one edge of the canvas overlapping the corresponding edge of the felt. The next layer consists of felt, of the same dimensions as those above named, also saturated with coal tar, and afterwards passed through and coated on both sides with a melted water-proofing composition, and having been prepared, as aforesaid, said layer c is arranged upon the canvas in the same manner that the canvas was arranged upon the felt layer below it, as described. Upon this layer c is arranged in like manner a strip of felt saturated in coal tar, when the whole strip is passed longitudinally between suitable pressing-rollers, which compress and form the different strata into one strip, A, which may be rolled up for storage or transportation in strips of any desired width and length.

A very important feature in my invention, and one which is applicable to all kinds of ready-made roofing of this class alike, is the mode of overlapping the various strata composing the roofing, whether of three, four, or more layers, a, b, c, d, and so on, so that the edges of the strips which overlap each other, when laid upon the roof, are thinner than the body of the strips, and thus when laid are at the laps only of the same thickness substantially as at the other parts of the roof, thus obviating the formation of ridges or gutters across the roof to retain rain and snow at the points where the strips join, which would obviously be the case if the overlapping edges of the strips were not constructed in the manner herein shown.

My invention, in regard to this roofing, consists, then, of two points, one of which is the roofing composed of the layers of material specified, whether the provision for thinning the edges of the strips is used or not; and the other consists in the overlapping of the edges of the different strata of material composing the strips of roofing, whether said layers are four in number, and the same as herein described, or whether there be more or fewer or other layers composing the strips of roofing A.

This roofing may be applied readily by any one, by arranging it upon the roof as shown and described, and securing the same in any suitable manner, and the ordinary gravel coating may then be put on, if desired.

Having described my invention, I will now specify what I claim, and desire to secure by Letters Patent:

1. I claim so arranging the several layers of material used in forming the strips of felt-roofing, as to make the edges of said strips thinner than the central portions, substantially in the manner and for the purposes specified.
2. I claim, as a new article of manufacture, the roofing-strips, composed of the material and arranged in the several layers herein specified.

JOHN SCANLAN.
